UNITED STATES PATENT OFFICE.

LESTER KIRSCHBRAUN, OF CHICAGO, ILLINOIS.

FLOOR COVERING AND PROCESS OF MAKING SAME.

Application filed June 24, 1918, Serial No. 241,655. Renewed July 10, 1920. Serial No. 395,385.

To all whom it may concern:

Be it known that I, LESTER KIRSCHBRAUN, a citizen of the United States, residing in the city of Chicago, county of Cook, and 5 State of Illinois, have invented certain new and useful Improvements in Floor Coverings and Processes of Making Same, of which the following is a specification.

This invention relates to floor coverings 10 and process of making same and refers more particularly to a colored bituminous composition adapted for use as floor covering. In a prior application of mine, Serial No. 222,938, I describe a process of making a 15 colored bituminous composition adapted for a wide variety of uses. The present invention is directed more particularly to a colored bituminous floor covering.

Among the salient objects of the invention 20 are to provide a product which consists essentially of a felted or similar base saturated or impregnated with a bituminous composition of any desired color and which is covered with a paint coating upon which is 25 printed a symmetrical design of any desired configuration; to provide a product in which the base or backing material is saturated with a hydrocarbon composition substantially free from the black compounds; to 30 provide a product in which the saturation for the base may be made either by distillation of the desired hydrocarbon or by the mixture of the hydrocarbon with a suitable hardener such as resin or other gum; to 35 provide a product in which the backing or base material may have one or both sides covered with a fabric re-enforcement which also may serve to receive the design; to provide a novel process for making the product 40 in question and in general to provide improvements of the character referred to.

In certain kinds of inexpensive rugs and 45 substitutes for linoleum now on the market, the design is printed upon a felted base saturated with a suitable bituminous composition such as asphalt or coal tar pitch. These bituminous compositions are of course black and considerable difficulty has been experienced in preventing the black color of 50 the base from discoloring the paint forming the design. Furthermore as the printed design wore off it left exposed the unsightly black base. These difficulties have limited the use of such material to the most inexpensive rug products or linoleum substitutes. 55

I have discovered that a rug or linoleum

substitute can be made from the felted base upon which is printed a design which will be not only sufficiently attractive but sufficiently permanent to be able to compete 60 with the more expensive products on the market. To this end I saturate the base with a bituminous composition of a permanent color which color can be of substantially any desired shade or tone which can 65 be adapted to the background of the printed surface. Furthermore, in some cases I have found that it may be desirable to paint the background which receives the design upon a relatively thin fabric facing or re-enforcement such as canvas applied to the face of 70 the felted base or foundation. This canvas fabric may be saturated with the same colored bituminous composition as is the base. The use of this fabric facing or re-enforcement gives to the finished article an 75 upper surface which has the appearance of a nap and avoids the smooth glossy surface which is likely to be found where the design is printed directly onto the felted base. The nap appearance can be accentuated by substituting for canvas facing or re-enforcement, a fabric which has a more pronounced 80 nap such as one having a villous surface giving it more of a velvety appearance. As 85 above stated the colored bituminous saturation may be made by distillation of hydrocarbons. In this case I take wax tailings resulting from distillation of petroleum and distill them down to the desired consistency 90 preferably with super-heated steam, thereby removing the volatile and more fluid and oily constituents. The pitch so obtained is then mixed with a suitable coloring agent which may be either a pigment or soluble 95 dye of the desired color or the dye and the pigment may be both used at the same time. The felted base is then saturated with this colored bituminous composition and in case the canvas or other facing is used, it is likewise 100 also saturated along with the base. The saturant acts as a binder to hold the fiber facing fixedly to the felted base. The facing and the base may be both put through the saturating tank and the pressing rolls at 105 the same time, the result being a substantially unitary structure.

After the base or the base and facing have been saturated as above described, they are then covered with a suitable coating material preferably by a paint forming the background of the desired color. On this back-

ground is then printed the design. Inasmuch as the saturant is of a color similar to the color forming the background, the wearing away of the paint which forms the background will not show a distinct color such as the case where the base is saturated with a black bitumen. This avoids any tendency to give a blotchy or unsightly appearance. The printing of the design is accomplished in a manner well known to those skilled in the art.

I have described above the formation of the saturation by the distillation of the wax tailings. In certain cases it may not be advantageous or desirable to distill the wax tailings for if, the wax tailings are distilled, the resultant distillate has to be suitably disposed of; I have discovered that the wax tailings can be brought to the desired consistency by a suitable hardening agent instead of the distillation. This may be accomplished by mixing the more or less semi-solid wax tailings with common rosin or analogous gums which gums, however, must be of such a character that they will not impart a black color to the resulting composition. The amount of rosin used, of course, depends upon the consistency of the wax tailings and the consistency desired in the resultant product. I have found in certain cases that from 20 to 60 per cent of rosin will answer the purpose. The product so made is brownish in color in mass and of a yellowish hue by transmitted light. The product so made can be used as the saturant material in exactly the same way as that made by distillation of the wax tailings heretofore described.

In order that the invention may perhaps be more clearly understood, I have shown a drawing in which the single figure designates a transverse sectional view of the product in which *a* is the felted base and *b* the fabric facing.

I claim as my invention:

1. A product of the character described consisting in a felted base and a fabric facing each saturated with a colored bituminous composition formed from wax tailings,

containing a coloring agent, a background 50 painted on the upper face and a design printed on the background.

2. A product of the character described, consisting in a felted base saturated with a colored bituminous composition formed 55 from wax tailings containing a coloring agent and a design formed in the upper surface of the base.

3. A product of the character described 60 consisting in a felted base and a fabric facing each saturated with a colored bituminous composition formed from wax tailings containing a coloring agent, and a design printed on the facing.

4. A product of the character described 65 consisting in a felted base and a fabric facing, the latter being saturated with a colored bituminous composition formed from wax tailings containing a coloring agent, and a design printed on the facing.

5. A product of the character described, consisting in a felted base saturated with a bituminous composition and formed from 70 wax tailings, a soluble dye dissolved in the wax tailings and giving a distinct color 75 throughout the base.

6. A product consisting of a fibrous sheet saturated throughout with a light colored bituminous binder capable of being colored and retaining the color, of a coloring agent 80 of distinctly different color than the binder and thoroughly incorporated with the binder.

7. A product of the character described 85 consisting in a felted base saturated with a light colored bituminous composition formed from a colorable hydrocarbon and a coloring agent contained in the hydrocarbon and giving a distinct color to the base.

8. A product of the character described, 90 consisting of a felted base saturated with a light colored bituminous composition obtained from the distillation of petroleum oil and a coloring agent contained in the bituminous composition and giving a distinct color 95 to the base.

LESTER KIRSCHBRAUN.
